Primary Examiner—Nelson C. Holtje*Assistant Examiner*—Martie Thompson*Attorney, Agent, or Firm*—Dunlap, Codding & Lee**[57] CLAIM**

The ornamental design for a flower pot cover, as shown and described.

DESCRIPTION

FIG. 1 is a top perspective view of a flower pot cover showing our new design;

FIG. 2 is a reduced side elevational view thereof;

FIG. 3 is a reduced top plan view thereof;

FIG. 4 is a reduced bottom plan view thereof;

FIG. 5 is a reduced side elevational view of a second embodiment of our design; and,

FIG. 6 is a reduced side elevational view of a third embodiment of our design.
